UNITED STATES PATENT OFFICE.

SAMUEL M. BEERY, OF INDIANAPOLIS, INDIANA.

SECTIONAL WHEEL-RIM.

1,090,513.

Specification of Letters Patent.

Patented Mar. 17, 1914.

Application filed August 20, 1913. Serial No. 785,622.

To all whom it may concern:

Be it known that I, SAMUEL M. BEERY, a citizen of the United States, residing at Indianapolis, in the county of Marion and State of Indiana, have invented a new and useful Improvement in Sectional Wheel-Rims, of which the following is a specification.

My invention relates to an improvement 10 in the class of sectional wheel-rims used for securing upon them the beaded outer casings covering the inner inflatable tubes, or resiliently-cushioning fillings forming the tires for automobile-wheels.

15 The present rim, while intended for general use, is more especially designed for securing, at its beaded edges, the outer casing covering the tire-filling which forms the subject of my application for Letters Patent 20 filed concurrently herewith on the 20th day of August, 1913, Serial Number 785,625; and it is illustrated in the accompanying drawings, in which—

Figure 1 is a broken view in elevation of 25 a wheel provided with my improved tire-holding rim; Fig. 2 is an enlarged section on line 2, Fig. 1, showing the split ring in its condition before being tightened in place by the outer wedging ring; Fig. 3 is a view 30 like that presented in Fig. 2, but without the inner tube and broken, and showing the split ring as tightened in place by the outer wedging ring; and Fig. 4 is a plan view of a section of the split ring and outer wedging ring.

The body of my improved rim is an annulus 6 fitting and fastened about a wheel-felly 7, and provided about its inner edge with a flange 6' against which abuts a ring 40 8 having its inner face undercut to receive and confine the adjacent bead of a rubber tire-casing 9. An aperture 10' is shown to be provided in the annulus 6 for protrusion through it of the nipple 10 of an inner inflatable rubber tube 11 when my rim is used for fastening thereon a pneumatic tire. At 45 intervals about the outer edge of the annulus are provided inwardly-extending lugs or ears 12 containing threaded holes 13. For 50 clenching the casing at its outer bead a split resilient ring 14 is provided to encircle the annulus 6, this ring having its inner face undercut to fit against the outer casing-bead and its outer face beveled, as shown at 14'.

55 With a casing 9 about the annulus 6 cov-

ering an inner tube (or a solid annular filling body) and its beads in place to be entered into the undercut faces of the rings 8 and 14, an outer ring 15 is fastened to bear against the edge of the annulus. This outer ring is provided, at intervals corresponding with those at which the lugs or ears 12 extend on the annulus 6, with similar lugs or ears 16 containing holes 17; and it is fastened in place by bolts 18 passed through the registering holes 13 and 17 in coinciding lugs or ears 12 and 16. On the inner edge of the ring 15 are provided, at intervals, inwardly-projecting lips 19 beveled on their under edges at a different angle from the bevel of the outer face of the split ring to engage that face wedge-like. In tightening the bolts 18, the lips 19 are wedged against the beveled outer face of the ring 14 which is thereby stretched about the respective 75 casing-bead to bring the split ends more or less closely together, thereby tightly confining the casing at its beads in the opposite undercut faces and at the same time tightening the split ring about the annulus 6 to 80 fasten the casing rigidly thereon.

My improved rim-construction thus serves to securely hold a tire in place, and renders the tire easily and quickly removable and replaceable, since to remove a tire it is only required to withdraw the bolts for taking off the ring 15, thereby freeing the split ring and releasing the tire, for its removal, to be repaired or to be replaced by a new one, which last-named operation may be as easily 90 and quickly performed as that for removing the tire.

It will be understood that the wedging members 19 are formed as spaced lips for the sake of lightness; but it would be within 95 my invention to form them as a continuous annular lip for the wedging purpose. Moreover, other details of the described construction may be variously modified without departure from my invention.

What I claim as new and desire to secure by Letters Patent is—

1. A sectional tire-rim comprising, in combination, an annulus adapted to encircle and be secured to a wheel felly, means co-acting 105 with one edge of said annulus adapted to act with and hold one side of a tire, a split ring having its radially outer face beveled encircling the other edge of said annulus, and means having a lateral movement to- 110

ward the felly adapted to co-act with the beveled face of said split ring to clamp the tire to the rim.

2. A sectional tire-rim comprising, in combination, an annulus to encircle and be secured about a wheel felly, and provided about one edge with a retaining ring, a split ring having its radially outer face beveled encircling the annulus at its opposite edge, and a ring releasably fastened to said opposite edge of the annulus, and provided with lips adapted to engage with a wedge-action the said inclined face of the split ring, for the purpose set forth.

15 3. A sectional tire-rim comprising, in combination, an annulus to encircle and be secured to a wheel-felly and provided about its inner edge with a ring having an undercut inner face, a split-ring encircling the 20 annulus, having an undercut inner face and a beveled outer face, and an outer ring releasably fastened to the outer edge of the annulus and provided with wedging lips en-

gaging the beveled face of the split ring, for the purpose set forth.

25 4. A sectional tire-rim comprising, in combination, an annulus to encircle and be secured to a wheel-felly and provided about its inner edge with a flange and about its outer edge with inwardly-projecting ears, 30 a ring about the annulus confined by said flange, a split ring encircling the annulus and having a beveled outer face, said flange-confined ring and split ring being formed to confine between them a tire casing at its 35 beaded edges, an outer ring having inwardly-projecting ears and wedging lips, and bolts passing through coincident ears on the annulus and said outer ring to fasten the outer ring to the annulus and wedge said 40 lips against the beveled face of the split ring, for the purpose set forth.

SAMUEL M. BEERY.
